PORTABLE VOTING BOOTH

Edward J. Crossland, Frank L. Walters, and Don Randall,
Tulsa, Okla., assignors to Seismograph Service Corpora-
tion, Tulsa, Okla., a corporation of Delaware

Continuation of design applications Ser. Nos. 58 and
59, Dec. 3, 1965. This application Apr. 23, 1968,
Ser. No. 11,746

Term of patent 14 years

Int. Cl. D3—99

U.S. Cl. D87—1

FIG. 1

FIG. 2

FIG. 3

FIG. 4

FIG. 5

FIG. 6

FIG. 7

FIG. 8

FIG. 9

FIG.10

FIG.11

FIG.12

FIG.13

FIG. 1 is a perspective view of a portable voting booth in a closed position according to the present invention;

FIG. 2 is a top view thereof;

FIG. 3 is a bottom view thereof;

FIG. 4 is a back view thereof;

FIG. 5 is a front view thereof;

FIG. 6 is a left side elevational view thereof;

FIG. 7 is a right side elevational view thereof;

FIG. 8 is a perspective view of the portable voting booth in an open position according to the present invention;

FIG. 9 is a front elevational view thereof;

FIG. 10 is a rear elevational view thereof;

FIG. 11 is a left side elevational view thereof, the right side being a mirror image of the side shown;

FIG. 12 is a top plan view thereof; and

FIG. 13 is a bottom plan view thereof.

This is a continuation of design applications Ser. Nos. 58 and 59, both filed Dec. 3, 1965, and both now abandoned.

We claim:

The ornamental design for a portable voting booth, substantially as shown and described.
